UNITED STATES PATENT OFFICE.

JACOB PEARSON, OF MINNEAPOLIS, MINNESOTA.

SLIDING-DOOR LOCK.

1,243,548.

Specification of Letters Patent. Patented Oct. 16, 1917.

Application filed July 29, 1916. Serial No. 112,141.

To all whom it may concern:

Be it known that I, JACOB PEARSON, a citizen of the United States, residing at Minneapolis, in the county of Hennepin and State of Minnesota, have invented certain new and useful Improvements in Sliding-Door Locks; and I do hereby declare the following to be a full, clear, and exact description of the invention, such as will enable others skilled in the art to which it appertains to make and use the same.

This invention relates to new and useful improvements in a sliding door lock and one of its objects is the provision of a device of this character, which shall be simple, durable and efficient, and which may be manufactured and sold at a comparatively low cost.

Another object of this invention is to provide a casing for receiving a bolt and having means therein for an engagement with the bolt to lock it against withdrawal therefrom.

A further object of this invention is to provide a catch pivoted in said casing and having means secured thereto for normally holding the free end thereof into an engagement with the bottom of the casing, whereby upon insertion of the bolt in the casing, the catch will engage the bolt and lock same against withdrawal.

A still further object of this invention is to provide a plate for pivotally supporting the bolt and having means thereon for supporting the bolt in a substantially horizontal plane and which is capable of allowing the bolt to be swung upon its pivot to depend downwardly therefrom.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:—

Figure 1 is a front elevation of a sliding door lock, constructed in accordance with my invention, illustrating it applied to a pair of sliding doors,

Fig. 2 is a longitudinal sectional view taken on the line 2—2 of Fig. 1,

Fig. 3 is a transverse sectional view taken on the line 3—3 of Fig. 1,

Fig. 4 is a transverse sectional view taken on the line 4—4 of Fig. 2, illustrating means for supporting the bolt in a horizontal plane, 60

Fig. 5 is an end elevation of the device, illustrating the free end of the catch, and

Fig. 6 is a plan view of a handle for operating the catch from the opposite side of the doors from which the device is mounted. 65

Referring in detail to the drawing, the numeral 1 indicates a door frame having slidably mounted thereon in any suitable manner doors 2 and 3, to which my invention is applied. A casing 4 consisting of a bottom wall 5 having secured to each edge thereof side walls 6 which are cut away as illustrated at 7 to dispose the free end of a catch 8 that is pivoted to the side walls 6 as illustrated at 9. The pivoted end of the catch 8 is spaced from the bottom 5 for the reception of a locking bolt 10, which will be hereinafter more fully described. The base 5 has bolts 11 extending therethrough and which extend through the door 2 to receive nuts 12 for securing the casing 4 to the door.

A plate 13 is secured to the door 3 adjacent the casing 4 by a bolt 14 which projects beyond the plate 13 and has pivoted thereto the locking bolt 10 which is provided at its free end with a projection 15 to engage the free end of the catch 8. A lug 16 is formed on the plate 13 and extends forwardly therefrom for supporting the locking bolt 10 in a substantially horizontal plane and which will allow the locking bolt to be swung about its pivot to depend downwardly from the plate when desired to prevent the bolt from projecting beyond the door when the door is in an opened position. 95

When desiring to lock the doors 2 and 3 together, the locking bolt 10 is swung to a substantially horizontal position and by moving the doors 2 and 3 in the direction of each other, the locking bolt 10 will enter the casing 4 between the base 5 and the catch 8 and the catch 8 will engage the notch 15 upon the locking bolt and lock same against withdrawal from the casing, thus preventing the doors from being moved apart or into an open position. A plate 17 is secured to the catch 8 upon its pivot end and has secured thereto a coil spring 18 which in turn is secured to a transversely extending strip 19 secured to the upper edges 100

105

110

of the side walls 6, providing a construction which will force the free end of the catch 8 into an engagement with the notch 15 upon the locking bolt, providing a device which 5 will automatically lock the bolt against withdrawal from the casing upon insertion therein. A suitable handle 20 is secured to the free end of the catch 8 for disengaging the catch 8 from the locking bolt when 10 desired.

A substantially L-shaped rod 21 extends through the door 2 and has one of its arm portions secured to the catch 8 and has mounted upon the free end of the other arm portion 15 a handle 22, whereby upon pushing on the handle 22, the catch 8 may be disengaged from the locking bolt 10 from the opposite side of the door from which the device is applied, so that a person may manipulate 20 this device from either side of the doors.

While I have shown and described the preferred embodiment of my invention, it will be understood that minor changes in construction, combination and arrangement 25 of parts may be made without departing from the spirit and scope of the invention as claimed.

Having thus described my invention, what I claim is:—

1. A lock comprising a casing, a bolt extending into said casing, a catch pivoted within the casing, a plate secured to the pivoted end of the catch, a spring connected to said plate, a transverse strip secured to the

casing and to the spring for causing the 35 spring to urge the free end of the catch into engagement with the bolt.

2. A lock comprising a casing consisting of a bottom wall and a pair of side walls, said side walls having their forward ends 40 inclined from a point intermediate their ends in the direction of their forward ends, a locking bolt received between the side walls and overlying the bottom wall and having its forward end projecting beyond 45 the walls, a lug formed on the forward end of said bolt, a catch pivoted between the side walls at a point adjacent the rear end, said catch having its forward end reduced and adapted to engage the lug upon the 50 locking bolt, a strip connected to the edges of the side walls adjacent the rear ends and adapted to overlie the catch for limiting the outward movement of the free end thereof from the side walls, a plate secured to the 55 pivoted end of the catch and projecting beyond the catch and terminating in a plane with the strip, and a coiled spring connected to the plate and to the strip for normally urging the free end of the catch into engagement with the lug upon the locking bolt.

In testimony whereof I affix my signature in presence of two witnesses.

JACOB PEARSON.
